UNITED STATES PATENT OFFICE.

HARRY T. HOPWOOD, OF CLEVELAND HEIGHTS, OHIO, ASSIGNOR TO THE EATON AXLE & SPRING COMPANY, OF CLEVELAND, OHIO, A CORPORATION OF OHIO.

BUMPER.

Application filed March 16, 1927. Serial No. 175,673.

This invention relates to improvements in bumpers for automobiles, and particularly to means for cheaply and effectively ornamenting the same.

5 In order to have bumpers present an attractive appearance, it is common practice to nickel-plate the impact receiving bars. Such bars in full size bumpers are rather large and require bulky and expensive equipment for the nickelizing operation. Furthermore, the buffing of the nickel is partially a hand operation which involves considerable labor and adds to the cost.

10 One of the objects of the present invention is to provide a finish for bumper bars which shall be at least the equivalent in good appearance of the fully nickelized bar but which shall involve only a fraction of the cost of production of the fully nickelized bar.

15 Another object is the provision of means which shall permit the use of material of a given section for impact withstanding bars and a given kind of ornamental wire upon 20 any and all types of bumpers, thus keeping the material requirements of a given manufacturing establishment at a minimum.

25 Other objects of the invention and the features of novelty will appear from the following description taken in connection with the accompanying drawings, in which:

30 Fig. 1 is a plan view of a fender guard embodying my invention;

35 Fig. 2 is an elevation of the structure shown in Fig. 1 looking in the direction of arrow 2 of Fig. 1;

40 Fig. 3 is an end elevation looking in the direction of arrow 3 of Fig. 1;

45 Fig. 4 is a detail sectional view on line 4—4 of Fig. 3, showing the parts on a larger scale;

50 Fig. 5 is a section of a bumper bar taken on line 5—5 of Fig. 2 but on a larger scale; and

55 Figs. 6 and 7 are sectional views corresponding to Fig. 5 but showing modifications.

In the drawings I have illustrated my invention as applied to a fender guard for use 60 at the rear of an automobile, but such showing is for purposes of illustration only as the invention is equally applicable to other types of bumpers. In the drawings, 10 is a transverse bar which acts as a tie between the impact withstanding portions of the bumper on

opposite sides of the automobile. To this transverse bar are secured, by means of bolts 11, or the like, supporting bars 12 and 13 which at their other ends carry plates 14 and 15 that are roughly triangular in shape and 60 are secured to the bars by any suitable means, as by rivets 16.

The plates 14 and 15 constitute the supports for a pair of superposed spaced impact withstanding bars 17 and 18, the latter being 65 secured to the plates by bolts 19. In each of the bars 17 and 18 there are formed one or more grooves 20 extending throughout the length of the bar and preferably parallel to its length. These grooves may be 70 most economically formed in the bar during the rolling operation at the time of its manufacture. In each groove I mount an ornamental wire 21 preferably formed to fit the groove more or less snugly. These wires are 75 cut from a coil which has been treated in some manner to give it an attractive and lasting finish as, for instance, nickel-plating, and they are preferably of a color which contrasts with the color of the bar. A bar enameled or painted in black or some dark color 80 provides a good background for nickelized wire.

The wire is held in place in its groove by some suitable method of attachment. That 85 here illustrated consists of clamps at the ends of the bars, and as a convenient clamping means I utilize the plates 14 and 15 which serve also to support the bars. These plates overlie the wires 21 and are drawn 90 up tightly into contact with the same by nuts 19' on the bolts 19, which latter extend through aligned holes in the bars and plates, the center wire 21 being cut a little shorter than the outer ones so as to clear the bolts. 95 Each bar 17 or 18 is therefore mounted on the plate 14 or on the plate 15 and the corresponding ends of its wires 21 are clamped in place all by a single bolt 19 and nut 19'. The wires 21 may also be secured in position by spot welding them to the bars 17 and 18 at the ends of the wires, and also at intermediate points.

100 While I have illustrated in my preferred form wires 21 of round cross-section, obviously wires of other cross-sections may be employed if desired, and as examples of such other cross-sections, I have illustrated in Figs. 6 and 7 respectively square wires 22 and half round wires 23.

Various modifications are possible without departing from the spirit of the invention, and I therefore desire to have it understood that the foregoing description and the accompanying illustrations are not intended as limitations upon the invention which, however, I desire to cover specifically as well as broadly in the appended claims.

Having thus described my invention, I claim:

1. A bumper bar having its impact withstanding portion formed of steel of suitable cross-section, and an ornamental portion comprising a plurality of wires of a color contrasting with that of the impact withstanding portion, said wires running parallel to the length of the bar, secured thereto and projecting outwardly therefrom.

2. A bumper bar having a plurality of spaced longitudinal grooves in the face thereof, and an ornamental wire mounted in each groove and secured therein, said wires projecting from the surface of the bar, whereby an ornamental ribbed structure is produced. 20

3. A bumper bar having a plurality of spaced longitudinal semi-circular grooves in the face thereof, and a wire of circular cross section mounted in each groove and secured therein, approximately half of each wire 30 projecting from the surface of the bar, whereby an ornamental ribbed structure is produced.

In testimony whereof, I hereunto affix my signature.

HARRY T. HOPWOOD.
